WILLIAM TOTHEROH, OF READING, PENNSYLVANIA.

Letters Patent No. 80,519, dated July 28, 1868.

IMPROVEMENT IN LAMPS.

The Schedule referred to in these Letters Patent and making part of the same.

TO ALL WHOM IT MAY CONCERN:

Be it known that I, WILLIAM TOTHEROH, of Reading, in the county of Berks, in the State of Pennsylvania, have invented a new and improved Burner for Coal-Oil and other Lamps; and I do hereby declare that the following is a full, clear, and exact description of the same, reference being had to the accompanying drawing, and to the letters of reference marked thereon, making part of this specification—

Figure 1 being an elevation showing the fans or guards for promoting combustion, the chimney-support, and the wick-tube, and

Figure 2 being a back elevation of the same.

Similar letters refer to similar parts in both views.

Instead of introducing the air to the flame through a perforated plate, as usual, I dispense with it and the centre web for supporting the chimney, and substitute for them a raised band or ring, A, supported on the base, B, of the burner by two or more legs a a', so that the air may have a free and uninterrupted pass to the flame. The wick-tube b is soldered air-tight in the body of the lamp-burner to prevent its overflow from carrying the flame into the lamp, and thereby exploding it. To assist in inserting the wick into the tube, I fix a spread or inwardly-curving wing c to its lower end.

Fixed to the inner side of the ring A are the three-sided uprights C C', one on each side of the wick-tube, parallel with its sides. D D' are two outwardly-curving deflectors attached to the uprights C C', and so placed as to lean over the edges of the tube, the one top being raised slightly above that of the other. The object of this arrangement is to deflect the current of air, and direct it against the flame, so as to render combustion more intense, giving a brighter, whiter, steadier flame, and consuming the fuel so completely that a considerable saving of oil is effected thereby. An important advantage gained by using an open ring, A, for carrying the chimney, is that an even temperature, both inside and outside, is had, thereby preventing any sudden influx of cold air, or increase of the temperature within the chimney, from breaking it, by causing the glass to contract unequally.

To obviate the necessity of unscrewing the burner from the lamp every time it requires replenishing with oil, I provide it with a filling-tube, E, beginning in a funnel-shaped mouth, and extending below the wick-tube in the lamp.

F is a ring or band, which is secured to a ring, G, which takes over the ring A, by the curved arms H H, &c. I is a globe, which rests on the said curved arms, and prevented from moving horizontally by the said band F.

The chimney J and the globe I being entirely open at their lower ends, it is not requisite that either should be removed while lighting the lamp. Fire can be applied to the wick from beneath.

What I claim as my invention, and desire to secure by Letters Patent, is—

1. The uprights C C', deflectors D D', ring A, rings or bands F and G, and the arms H, when combined and arranged as shown and described.
2. The uprights C C', deflectors D D', ring A, base, B, filling-tube E, wick-tube b, and the outwardly-curving wing or guide c, when combined and arranged as shown.

In testimony whereof, I hereunto sign my name to this specification in presence of two subscribing witnesses.

WILLIAM TOTHEROH.
